(57) **CLAIM**

The ornamental design for a woodworking machinery electronic control panel as shown and described.

DESCRIPTION

FIG. 1 is a perspective view of a woodworking machinery electronic control panel showing my new design;

FIG. 2 is a front view thereof;

FIG. 3 is a rear view thereof;

FIG. 4 is a side view thereof;

FIG. 5 is an opposite side view thereof;

FIG. 6 is a top plan view thereof; and,

FIG. 7 is a bottom plan view thereof.

1 Claim, 7 Drawing Sheets

FIG.1

FIG.2

FIG.3

FIG.4

FIG.5

FIG.6

FIG.7
